APPARATUS FOR FRACTIONATING HYDRO-CARBON OIL VAPOR

Frank W. Hall, Port Arthur, Tex., assignor to
The Texas Company, New York, N. Y., a corporation of Delaware

Application June 15, 1932, Serial No. 617,318

7 Claims. (Cl. 196—139)

This invention relates to the fractionation of hydrocarbon oil vapors and particularly to an improved apparatus for fractionating developed vapors into one or more liquid fractions and a 5 final vapor fraction.

The invention contemplates the rectification of hydrocarbon oil, cracked or uncracked, under such favorable conditions as to effect the complete separation of desired fractions. It further contemplates providing an improved type 10 of apparatus peculiarly suited for the efficient contacting of the vapors undergoing fractionation with refluxing liquid to promote the refluxing of the heavier constituents of the vapors and the 15 reboiling of the lighter constituents of the refluxing liquid while providing adequate length and area of the contact passage for the advancing stream of vapors to obtain sharp fractionation thereof.

20 The invention is adaptable to fractionators and dephlegmators of various types, the apparatus being of relatively light construction in which the expense of fabrication and handling may be reduced to a minimum. Moreover, the apparatus 25 may be constructed of comparatively expensive corrosion-resistant material and because of the lightness of the structure the total cost should be approximately the same or even less than the cost of present fractionators made of ordinary 30 steel or iron, whereas the life of the apparatus disclosed herein will be greatly increased over that of the usual equipment in similar service.

The invention will be readily understood from a 35 consideration of the following description taken in connection with the drawings, in which:

Fig. 1 is a sectional view of a fractionating vessel taken in elevation, illustrating a preferred embodiment of the invention.

Fig. 2 is a sectional view taken on the line 2—2 40 of Fig. 1.

Fig. 3 is a sectional view of a fractionating vessel taken in elevation illustrating a modified form of the invention.

Fig. 4 is a sectional view taken on the line 4—4 45 of Fig. 3.

Referring to Figs. 1 and 2 of the drawings, a vessel 1 is shown having a vapor inlet 2 and a vapor outlet 3. A line 4 is provided through which a cooling liquid may be introduced into the upper 50 portion of the vessel 1 and distributed over the upper portion of the vessel 1 by a spreader plate 5. A line 6 is provided for withdrawing dephlegmated condensate from the bottom of the vessel. A plurality of oppositely inclined corrugated 55 baffles 7, 8, 9 and 10, whose corrugations run at

right angles to the direction of inclination of the baffles, are secured within inclined arcuate bands 12, 13, 14 and 15, fitted snugly against the inner wall of the vessel 1. The baffles are preferably perforated in the valley of each corrugation and the lower edge of each baffle terminates in an overflow wall short of the opposed vessel wall to form a gap therebetween to provide a passage for the vapors. Due to the reversed relation of successive baffles these gaps occur on opposite sides 10 of the vessel on adjacent baffles, thus providing a zig-zag path for the upwardly rising vapors. Any desired number of baffles may be employed. A sump or trap basin is provided in the upper portion of certain of the baffles, as shown at 16, 15 from which a trapped liquid may be removed through a drawoff line 18.

Referring now to Figs. 3 and 4 of the drawings, a vessel 20 is shown having a vapor inlet 21 and a vapor outlet 22, the latter being shielded by 20 a protecting plate 26. A supply pipe 23, formed with a spray outlet 24, is provided through which a cooling liquid may be introduced into the vessel and distributed over the interior of the vessel. The dephlegmated condensate may be withdrawn from the bottom of the vessel through the line 25. A plurality of corrugated baffles 30, 31 and 32 are secured in arcuate bands 33, 34 and 35, spaced throughout the interior of the vessel, the baffles being supported at an oblique angle on the inner wall of the vessel 20, as in the first form of the invention.

The baffles shown in this embodiment are in general similar to those shown in Figs. 1 and 2 and may be employed in any desired number, 35 but in this second form of the invention each baffle except the lowermost one is provided with an overhanging ledge 40 constituting a partition wall or plate which depends into an appropriate sump or trap basin 41 formed in the upper portion of the next succeeding baffle. The plates 40 and the associated liquid filled sumps 40 constitute liquid seals which cause the rising vapors to pass through the openings in the baffles 30, 31, etc., before reaching the vapor outlet 22. 45 The trap basins 41 are shown as provided with outlet pipes 36 and 38, leading out through the wall of the vessel 20 and through which different fractions may be removed.

The main purpose of the fractionating apparatus described herein is to afford a maximum amount of contact between the moving vapor stream and the continuously refluxing condensate, while permitting the accumulation and removal of the fractional condensate and to pro- 50 55

vide a maximum of heat absorbing surfaces on the transverse baffle plates without increasing the over-all size of the fractionating chamber and baffles. The apparatus tends to effect the smooth 5 and uniform advancement of the vapors through the fractionating column, and to enable the efficient separation of the oil into the desired fractions. The invention avoids to a large degree the mechanical entrainment and advancement of 10 liquid particles with the vapors and avoids mechanical inclusion and later solution of the lighter vaporous constituents with the down-flowing liquid. The invention thus effects a desirable sharp and close fractionation, such that the end 15 point of each succeeding fraction is approximately the same or slightly less than the initial boiling point in the preceding fraction.

In the operation of the apparatus shown in Figs. 1 and 2 the vapors may be introduced into 20 the lower portion of the vessel 1 through the line 2, the vapors moving across the space beneath the baffle 10, where they pass upwardly through the gap left between the edges of the baffles and the walls of the vessel. The vapors moving progressively upwardly through the vessel, thus move 25 back and forth in a zig-zag path, until they reach the vapor outlet 3. As the vapors are advanced and cooled the volume thereof is reduced, due to the condensation being effected, and it is accordingly possible to space the upper baffles more 30 closely together than the lower ones, as shown. This construction tends to maintain a relatively constant velocity of the vapors through the tower, thus tending further to balance the operation and to lengthen the path through which 35 the vapors move without increasing the height of the tower.

A regulated amount of cooling material, preferably a portion of the condensate from the vapors emerging from the vessel 1 through the outlet line 3, is returned through the pipe 4 and distributed over the upper baffle 7 by means of the plate 5, the liquid dropping downwardly through the rising vapor stream. A certain amount of vaporization of the reflux material will be effected, as well as some condensation of the vapor by 40 this contact between the relatively cool reflux liquid and the hotter vapor.

The corrugations in the baffles are formed of a 45 depth sufficient to maintain shallow pools of condensate in them at the angle at which the baffles are pitched. The liquid deposited on the baffles 7, 8, etc. cascades from pool to pool, due to the slope of the baffles. There is also a slow 50 passage of liquid through the small openings in the valleys of the corrugations, if these openings are employed, the size of these openings being preferably such as to effect a rather fast dripping or the flowing of a minute stream of liquid 55 from each shallow pool. Finally, the surplus of liquid that overflows the lowermost corrugation of each baffle drops downwardly through the rising vapor stream onto the next succeeding baffle. At this time, due to the intimate and complete vapor and liquid contact, there will be a 60 certain vaporization of the cooling liquid and condensation of the upwardly moving vapors.

The corrugated form of the baffles facilitates 65 the transfer of heat from the vapors to the baffles and from the baffles to the liquid. The shallow pools of heated condensate serve to expose the liquid material in a manner for effectively re-boiling the liquids, while the tortuous movement 70 of the vapors back and forth across the chamber 75 and the contact thereof with the reflux serve to

bring the vapors into thorough contact with the liquid for effecting uniform fractionation.

The sump or trap basin 16 catches the overflow from the baffle above and the trapped material may be withdrawn, or such portion as desired, any surplus of material caught in this basin overflowing and cascading over the baffle 9, together with the other liquid undergoing re-boiling. Any desirable number and arrangement 10 of trap baffles may be provided, depending upon the height of the fractionating vessel, the character of the vapors being fractionated and the number of fractions desired.

In the optional arrangement shown in Figs. 3 and 4 the trap basin at the lower edge of each 15 baffle seals the vapor passage and, with the construction disclosed, forces the vapors upwardly through the openings in the baffles. The liquid, however, flows downwardly as in the first form of the invention, cascading over the corrugated 20 baffles and flowing through the successive liquid seals formed at the sumps 41. In this form of the invention, the openings in the baffles 30, 31, etc., or their equivalent, are necessary, whereas in the form of the invention, illustrated in Figs. 25 1 and 2, the openings may be omitted.

The form of the invention illustrated in Figs. 1 and 2 operates with very little pressure drop throughout the tower. This construction is therefore particularly adapted for towers subjected to a relatively high vacuum. The form of the invention shown in Figs. 3 and 4 has a substantial pressure drop through the tower, when constructed of the usual height and with the usual number of trays. This apparatus requires accurate construction and proportioning as the 30 openings in the baffles are required to accommodate the entire volume of rising vapors. This 35 form of the invention is particularly applicable to towers operated under pressure.

Obviously many modifications and variations 40 of the invention as hereinbefore set forth may be made without departing from the spirit and scope thereof as set forth in the appended claims.

I claim:

1. Apparatus for dephlegmating hydrocarbon oil vapor comprising a closed vessel having a lower vapor inlet and an upper vapor outlet, a liquid outlet adjacent the lower portion of the vessel, and downwardly sloping vertically spaced transversely corrugated baffles affixed to alternate side walls of the vessel, the lower free edges of the baffles terminating short of the opposed walls of the vessel for forming successive gaps between the lower free edges of said baffles and the walls of 55 said vessel to provide a staggered vapor flow passage.

2. An apparatus for rectifying hydrocarbon vapors comprising an enclosed chamber having a lower vapor inlet and an upper vapor outlet, a liquid outlet at the lower portion thereof, a series of downwardly inclined staggered baffles projecting inwardly into said chamber from the side walls thereof intermediate said vapor inlet and said vapor outlet, each of said baffles being 60 formed of thin material with vapor receiving recesses on the lower surfaces thereof for affording large vapor contact surfaces thereon and with liquid receiving pockets for condensed liquid on the upper surfaces thereof, said baffles being 65 formed with unobstructed overflows at the lower edges thereof, the overflow of a preceding baffle discharging liquid onto the upper portion of a succeeding baffle.

3. Apparatus for rectifying hydrocarbon va- 75

5 pors comprising a vessel having a vapor inlet and a vapor outlet, a series of downwardly inclined baffles in the vessel, successive baffles being alternately inclined in the opposite direction, corrugations in the baffles extending at right angles to the direction of inclination of the baffles, successive baffles of said series being formed with depending lower edges and with basins adjacent their upper edges into which the depending edges 10 of the next higher baffles project.

10 4. Apparatus for fractionally condensing hydrocarbon oil vapors comprising a vessel having a vapor inlet and a vapor outlet, a series of downwardly inclined baffles in the vessel, successive 15 baffles being alternately inclined in the opposite direction, corrugations in the baffles extending at right angles to the direction of inclination of the baffles, perforations in the valleys of the corrugations, a cooling liquid connection leading into 20 the upper portion of the vessel, a spreader inside the vessel near the upper portion for distributing a cooling material over an upper baffle, successive 25 baffles of said series being formed with depending lower edges and with basins adjacent their upper edges into which the depending edges of the next higher baffles project and outlets provided for withdrawing liquid from certain of said basins.

30 5. In an apparatus for dephlegmating hydrocarbon oil vapors, an enclosed chamber formed with a vapor inlet and a vapor outlet for leading vapors upwardly through said chamber, a liquid outlet in the lower portion of said chamber, and downwardly inclined staggered baffle plates extending across the major portion of said chamber 35 and terminating short of the opposed chamber walls to provide a staggered vapor flow passage, each said baffle plate including a series of transversely arranged corrugations constituting liquid receiving pockets on the upper surface thereof, from which liquid overflows from one pocket 40 to another as it flows downwardly along the inclined baffle plate, and finally overflows from the lower end of the baffle plate and falls across the path of vapor flow, each said baffle plate also including a series of vapor receiving recesses on the under surface thereof for increasing the heat transfer from the vapor beneath the plate to the liquid 45 above the plate.

50 6. In an apparatus for dephlegmating hydrocarbon oil vapors, an enclosed chamber formed with a vapor inlet and a vapor outlet for leading vapors upwardly through said chamber, a liquid

outlet in the lower portion of said chamber, and downwardly inclined staggered baffle plates extending across the major portion of said chamber and terminating short of the opposed chamber walls to provide a staggered vapor flow passage, each said baffle plate including a series of transversely arranged corrugations constituting liquid receiving pockets on the upper surface thereof, from which liquid overflows from one pocket to another as it flows downwardly along the inclined baffle plate, and finally overflows from the lower end of the baffle plate and falls across the path of vapor flow, said pockets being provided with restricted drain openings adjacent the lower portions thereof through which limited quantities 10 of liquid flow and also fall across the path of vapor flow, each said baffle plate also including a series of vapor receiving recesses on the under surface thereof for increasing the heat transfer from the vapor beneath the plate to the liquid 15 above the plate.

20 7. Apparatus for rectifying and fractionally condensing hydrocarbon vapors, comprising a closed vessel having a lower vapor inlet and an upper vapor outlet, a liquid outlet adjacent the lower 25 portion of the vessel, a plurality of downwardly inclined baffle plates affixed to alternate side walls of the vessel intermediate the said vapor inlet and the said vapor outlet, the lower free edges of the baffle plates terminating short of the opposed walls of 30 the vessel for forming staggered gaps therebetween to provide a tortuous vapor flow path, each of said baffle plates being formed with a plurality of comparatively shallow liquid retaining pockets for receiving condensed liquid on the upper surface 35 thereof, from which liquid overflows from one pocket to another as it flows downwardly along the inclined baffle plate, and finally overflows from the lower free edge of a superposed baffle and falls across the path of vapor flow onto the next succeeding baffle, each of said baffle plates also including a series of vapor receiving recesses on the under surface thereof for increasing the heat transfer 40 from the vapor beneath the baffle to the liquid above the baffle, certain of said baffle plates being 45 formed with a comparatively deep liquid containing sump adjacent the side wall of the vessel, and a liquid offtake from said sump leading to the exterior of said chamber for side stream withdrawal.

50 FRANK W. HALL.
